(57) **CLAIM**

The ornamental design for a hair dryer, as shown and described.

DESCRIPTION

FIG. 1 is a front elevational view of a hair dryer showing my new design;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof;

FIG. 7 is a perspective view of the hair dryer; and,

FIG. 8 is another perspective view thereof.

The broken lines in the drawings are for the purpose of illustrating portions of the hair dryer that form no part of the claimed design.
